UNITED STATES PATENT OFFICE.

CLYDE HART, OF HUMBLE, TEXAS, ASSIGNOR OF ONE-HALF TO JOHN G. CARR, OF HARRIS COUNTY, TEXAS.

SPEAR.

Application filed April 1, 1926. Serial No. 99,122.

This invention relates to new and useful improvements in a spear.

One object of the invention resides in the provision of a very simple type of spear 5 designed for engaging with and pulling pipe from a well bore and which may be readily disengaged from the pipe in case it cannot be recovered.

Another object of the invention is to provide a spear of the character described having pipe engaging jaws and a mechanism operable by fluid pressure through which said jaws may be actuated into engagement with the pipe; said spear also embodying 15 means for normally holding said jaws out of engagement with said pipe.

With the above and other objects in view this invention has particular relation to certain novel features of construction, operation and arrangement of parts, an example of which is given in this specification and illustrated in the accompanying drawings, wherein:—

Figure 1 shows a vertical sectional view 25 of the device.

Figure 2 shows a cross sectional view taken on the line 2—2 of Figure 1.

Figure 3 shows a cross sectional view taken on the line 3—3 of Figure 1.

Figure 4 shows a vertical sectional view 30 of another form of the spear.

Figure 5 shows a cross sectional view taken on the line 5—5 of Figure 4, and

Figure 6 shows a cross sectional view 35 taken on the line 6—6 of Figure 4.

Referring now more particularly to the drawings, wherein like numerals of reference designate similar parts in each of the figures, the numeral 1 designates a downwardly flared mandrel whose lower end is tapered and carries a guide point 2. This guide point not only serves to guide the spear into the pipe to be pulled, but also serves as a bit to remove any earth, or clogging material that may be in said pipe. The downwardly flared surface of the mandrel 1 has the grooves or tracks 3, in which the jaws 4 are mounted to slide. The outer surfaces of these jaws are serrated, forming 45 teeth, which engage the pipe to be pulled.

The upper end of the mandrel is reduced and outwardly threaded and the cylinder 5 is screwed onto it and the upper end of this cylinder is connected to the string of pipe 55 6, through the coupling 7. In the cylinder

5 there is a plunger 8 whose upward movement is limited by the annular stop 9 secured within the coupling 7.

Depending from the plunger 8 there is an actuating rod indicated by the numerals 60 10, 10' in Figures 1 and 4 respectively. The lower ends of these rods work in the socket 11 in the mandrel 1. Surrounding each rod 10, 10' there is a coil spring 12 which rests on the corresponding mandrel and whose 65 upper end supports the plunger 8.

The lower end of the rod 10 is connected to the corresponding jaws 4 through the links 13, which work through slots 14, in the mandrel and whose ends are pivoted 70 to the rod 10 and to the respective jaws 4.

The lower end of the rod 10' is tapering and works between the upper ends of the links 13' which work through the slots 14' in the corresponding mandrel and whose 75 outer ends are pivoted to the corresponding jaws 4. The links 13' move lengthwise through their slots 14' and are retained therein by means of pintles 15 which are fitted through the lengthwise slots 16, in the links 13'. The jaws 4, in the form shown in Figures 4 to 6 are seated on the coil springs 18, as shown.

In order to engage the spear with the pipe to be pulled it is let down into the pipe and pump pressure is then applied to the fluid in the string 6 and this will force the plunger 8 downwardly and operate through the rod 10 and links 13, or through the rod 10' and the links 13', as 80 85 the case may be to force the corresponding jaws 4 downwardly and outwardly into engagement with the pipe to be pulled. The upper part of the cylinder 5 has relief ports 17 to relieve the pressure after the spear 90 is engaged with said pipe. An upward pull may now be exerted through the string 6 and the stuck pipe may be thus dislodged. 95

If the pipe cannot be recovered the pump pressure is cut off and the spear suddenly 100 forced downwardly and this will operate to release the jaws 4 from the pipe and the spring 12, shown in Figure 1, or the springs 16, shown in Figure 4, will then immediately carry said jaws up into released position and the spear may then be removed. 105

What I claim is:—

1. A spear including a mandrel having a downwardly flared portion provided with tracks, pipe engaging jaws mounted to slide 110

on said tracks and whose outer sides are formed with teeth, said mandrel having a deep socket therein forming a bearing, a cylinder associated with the mandrel, a plunger in the cylinder, a stop carried by the cylinder adapted to limit the upward movement of said plunger, an actuating rod carried by the plunger and working in said socket, a coil spring surrounding said rod and interposed between the upper end of the mandrel and the plunger, said mandrel having downwardly diverging slots leading from said socket through said mandrel, links working through said slots and pivoted at their lower ends to the corresponding jaws and whose upper ends are in operative connection with said rod, each link having a lengthwise slot therethrough forming a bearing and a pintle fixed to said mandrel and working through said bearing.

2. A spear including a mandrel having a downwardly flared portion provided with tracks, said mandrel also having an axial socket and slots diverging downwardly from said socket, jaws mounted to slide on said tracks, links pivoted at their lower ends to said jaws and working through said slots, a cylinder carried by the mandrel, a plunger therein, a rod carried by the plunger and adapted to work in said socket and operatively connected with said links, a coil spring around said rod and interposed between the mandrel and plunger and a stop in the cylinder adapted to limit the range of movement of the plunger.

3. A spear including a mandrel having a downwardly flared portion provided with

tracks, said mandrel also having an axial socket and slots diverging downwardly from said socket, jaws mounted to slide on said tracks, links pivoted at their lower ends to said jaws and working through said slots, a cylinder carried by the mandrel, a plunger therein, a rod carried by the plunger and adapted to work in said socket and operatively connected with said links, a coil spring around said rod and interposed between the mandrel and plunger and a stop in the cylinder disposed to limit the range of movement of the plunger.

4. A spear including a mandrel having a downwardly flared portion provided with tracks, said mandrel also having an axial socket and slots diverging downwardly from said socket, jaws mounted to slide on said tracks, links pivoted at their lower ends to said jaws and working through said slots, a cylinder carried by the mandrel, an actuating rod connected to the plunger and adapted to work in said socket, and operatively connected with said links, a coil spring around said rod and interposed between the mandrel and plunger and a stop in the cylinder adapted to limit the range of movement of the plunger and a coil spring interposed between each jaw and the mandrel and operating against said jaw and tending to move the jaw in one direction relative to the mandrel.

In testimony whereof I have signed my name to this specification.

CLYDE HART.

Certificate of Correction.

Patent No. 1,619,264

Granted March 1, 1925, to

CLYDE HABT.

It is hereby certified that the name of the assignee in the above numbered patent was erroneously written and printed as "John G. Carr," whereas said name should have been written and printed as *John D. Carr*, as shown by the record of assignments in this office; and that the said Letters Patent should be read with this correction therein that the same may conform to the record of the case in the Patent Office.

Signed and sealed this 29th day of March, A. D. 1927.

[SEAL.]

M. J. MOORE,
Acting Commissioner of Patents.
